US0D1067885S

(12) **United States Design Patent** (10) **Patent No.:** **US D1,067,885 S**
(45) **Date of Patent:** **** Mar. 25, 2025**

(54) **ELECTRICAL APPARATUS WITH A LINE SIDE ISOLATION SAFETY SWITCH**

(71) Applicant: **Eaton Intelligent Power Limited**,
Dublin (IE)

(72) Inventors: **Warren Sipe**, Cleveland, TN (US);
Jeffrey Ensley, Cleveland, TN (US)

(73) Assignee: **EATON INTELLIGENT POWER LIMITED**, Dublin (IE)

(**) Term: **15 Years**

(21) Appl. No.: **29/820,507**

(22) Filed: **Dec. 22, 2021**

Related U.S. Application Data

(60) Division of application No. 29/770,732, filed on Feb. 16, 2021, now Pat. No. Des. 942,401, which is a division of application No. 29/678,878, filed on Jan. 31, 2019, now Pat. No. Des. 913,247, which is a continuation of application No. 29/593,671, filed on Feb. 10, 2017, now Pat. No. Des. 853,970.

(57) **CLAIM**

The ornamental design for an electrical apparatus with a line side isolation safety switch as shown and described.

DESCRIPTION

FIG. 1 is a top, side perspective view of an electrical apparatus with a line side isolation safety switch showing our design;

FIG. 2 is a front view thereof;

FIG. 3 is a back view thereof;

FIG. 4 is a side view thereof;

FIG. 5 is an opposing side view thereof;

FIG. 6 is top view thereof; and,

FIG. 7 is a bottom view thereof.

The broken lines in the figures illustrate portions of the article that form no part of the claimed design.

1 Claim, 5 Drawing Sheets
